BIRD FEEDER

William M. Malloy, Sr., Stony Point, N.Y.
Application July 2, 1958, Serial No. 51,624

Term of patent 14 years

(Cl. D31—2)

Figure 1 is a side elevational view of a bird feeder showing my new design;

Figure 2 is an end elevational view thereof showing the valve on the left side in open position; and

Figure 3 is a transverse sectional view taken substantially along the line 3—3 of Figure 1.

Both sides of the feeder are identical, so that Figure 1 is a view of either side. Similarly, both ends of the feeder are identical, so that Figure 2 is a view of either end.

I claim:

The ornamental design for a bird feeder, as shown and described.
